UNITED STATES PATENT OFFICE.

THOMAS H. PERRY, OF BLOOMINGTON, ILLINOIS.

RAILWAY-FROG.

SPECIFICATION forming part of Letters Patent No. 352,066, dated November 2, 1886.

Application filed March 12, 1886. Serial No. 195,009. (No model.)

To all whom it may concern:

Be it known that I, THOMAS H. PERRY, a citizen of the United States, residing at Bloomington, in the county of McLean and State of Illinois, have invented a new and useful Railway Frog, (for which I have not obtained Letters Patent in any other country,) of which the following is a specification.

It is generally understood by those who are conversant with the construction and maintenance of railways that the tread of locomotive and car wheels wear next to their flanges three to four inches wide by from naught to three-quarters inch deep, (more or less, according to service,) and wearing the treads into a groove shape, leaving a flange, something similar to its gage-flange, formed on their outer rims. Such wheels are usually called "guttered," and this outer or guttered flange, falling below the bearing-tread, comes in contact with the members of a T-rail frog at their crossing points. This contact is in such manner an increment of forces that constitutes an extraordinary element of destruction, and is destructive, to a great degree, of the frog and the railway equipment operating it. Heretofore T-rail railway-frogs have been constructed without appliances or of a mechanism that overcame in the best manner this destructive effect of the outer flange of a guttered wheel.

My invention relates to improvements in T-rail railway-frogs, and the object of my improvements is to overcome the destructive effect of the outer flange of a guttered wheel at its point of crossing the several members of a T-rail frog. I attain this object by the mechanism illustrated in the accompanying drawings.

Figure 1 is the top view of a T-rail frog, and showing a guttered wheel tread relative thereto. Fig. 2 is a top view as the frog appears with my improvements. Figs. 3 and 4 are vertical sections of the improvements on the line 1 2 and 3 4, respectively; and Figs. 5 and 6 are vertical sections of the improvements on the line 5 6 and 7 8, respectively.

Similar letters refer to similar parts throughout the several views.

50 a a are the T-rail members that form the point of a T-rail frog.

b b are the wing-rails.

c is the outer flange of a guttered wheel.

d d are the lines traversed by the outer flange in either direction, and show the points 55 of impact e with the several frog members.

F is a filling-block, cast or forged of hard metal, or a combination of metals, fitting neatly in filling the acute angle of the diverging frog members a a. Its thickness vertically is 60 equal to the height of a frog from its base to tread-bearing face, and is carried back in full face with the frog from g to a line, h, where the distance across on h with the distance across one of the frog members a (and vice versa with 65 the opposite member) shall be not less than the width of the wheel-treads. At h the face of the block breaks to an incline, as an easing, and by which the guttered wheel-flange is carried up to and over the frog's face in 70 clearance of any impact at the points e of the frog members a a.

M is a metal block, neatly fitted and secured to the outer vertical face of the wing-rails b b. In its manner of construction and effective operation it is similar to the filling-block F--i. 75 e., it gives to the wing-rail a width of wheel-bearing tread and in supporting the guttered flange to the crossing point on a plane level with the frog's face. These blocks have the 80 inclined-face approaches as an easing, similar to the filling-block F, and by which the guttered flange is carried up to the frog's face and over the points of impact e of the wing-rails b b without a shock.

I am aware that prior to my invention T-rail frogs having various devices for their strength and durability have been constructed. I therefore do not claim such a combination, broadly; but

What I do claim as my invention, and desire to secure by Letters Patent, is—

1. The combination, in a frog, with the wing-rails, of the re-enforcing blocks located on the sides of the same, substantially as set 95 forth.

2. The combination, in a frog, with the wing-rails having the re-enforcing blocks, of the members a a and the filling-block between them, substantially as set forth.

THOMAS H. PERRY.
